CLAIM

I claim the ornamental design for a jacketed container with window, as shown and described.

DESCRIPTION

FIG. 1 is a top, front, right side exploded perspective view of a jacketed container with window showing my new design;

FIG. 2 is a bottom perspective view of the cap portion with the container portion removed for ease of illustration;

FIG. 3 is a top plan view thereof;

FIG. 4 is rear elevational view of the jacketed container with window of FIG. 1, shown in the closed position;

FIG. 5 is a left side elevational view thereof;

FIG. 6 is a right side elevational view thereof; and,

FIG. 7 is a front elevational view thereof.
